UNITED STATES PATENT OFFICE.

FELIX BENEDICT HERZOG, OF NEW YORK, N. Y.; HENRIETTA HERZOG EXECUTRIX OF SAID FELIX BENEDICT HERZOG, DECEASED.

ELECTRIC SIGNALING APPARATUS AND CIRCUITS.

1,126,007.

Specification of Letters Patent.

Patented Jan. 26, 1915.

Original application filed April 8, 1889, Serial No. 306,474. Divided and this application filed February 10, 1902. Serial No. 93,282.

To all whom it may concern:

Be it known that I, FELIX BENEDICT HERZOG, Ph. D., a citizen of the United States, and a resident of the city, county, and State of New York, have invented a new and useful Improvement in Electric Signaling Apparatus and Circuits, of which the following is a specification.

This is a division or continuation of a pending case S. No. 306,474 filed on April 8, 1889, since patented on Feb. 11, 1902 as 5 693,013, and is to be considered as related to two other applications 93,281 $\frac{1}{2}$ and 93,283 $\frac{1}{2}$ filed on even date herewith as co-15 divisions of said original case.

This invention relates to improvements in electrical signaling or communication, and embodies various points of novelty herein described as in one organization and 20 also embodies various specific improvements whereby combinations of less than all the elements may advantageously be used separately.

All of the apparatus herein shown is designed for use at a receiving station in connection with a system in which various radiating lines go to substations at which there is a suitable apparatus, which, however, not being a part of the present invention, 25 is not referred to more specifically herein.

The apparatus herein set forth is of the type of visual indicator for receiving signals from variable signal transmitters at such 30 sub-stations.

In the drawings Figure 1 represents a section of half the apparatus in front elevation, Fig. 2 being a section of the same in elevation; Fig. 3 represents a plan of a portion of the mechanism designed to fit within 40 that shown in Fig. 1 as indicated by the corresponding letters; Fig. 3^a is a modification of a detail of Fig. 3, and illustrates a more complete form of the invention as to 45 one feature thereof, although the simpler form shown in Fig. 3 is ample for many purposes; Fig. 4 represents a rear view and Fig. 5 a front view of one of the elements of the apparatus, and Figs. 6, 6^a and 7 are 50 modified details of the same.

A type of the apparatus at the sub-station, which is designed to work in connec-

tion with the present one, is found in the Patent 693,013 issued on the application of which this is a division, and speaking generally consists of a variable signal transmitter in which the variation of the several signals coincides with the variation in the number of steps made by a step-by-step wheel. For a given organization such 55 wheel may have the same number of steps as that shown in the step-by-step wheel in Fig. 3 of the present apparatus. Such sub-station apparatus moreover is designed to be driven as the result of a number of impulses sent to line, and the present apparatus embodies means for sending such impulses. Such a sub-station apparatus, moreover, is designed to produce at the receiving station an initial effect to indicate 60 to the operator there that he is required to begin operations. This feature is also embodied in the present apparatus.

Referring to the figures in detail a suitable case A'' is divided by a partition B''' 75 so that a second case (Fig. 3) may fit into the same. The various circuit connections are made directly to strips Z Z of Fig. 1, and when the case of Fig. 3 is inserted in place suitable contact plates 1, 2 thereon go 80 into contact with these strips, and these plates 1, 2 are directly connected with the magnet L' and other circuit connections therein by lines 3 and 4, as shown in Fig. 3. Considering first the connection of the 85 step-by-step mechanism of Fig. 3 the magnet L' attracts an armature H', suitably fulcrumed on the bracket E'', and retracted by the spring I'' against a limiting stop and adjuncts, Q, Q', Q''. The armature H' 90 carries a driving pawl J'' normally held in position by a suitable spring I to drive the ratchet wheel L'', and in combination with a retaining pawl J' held in place by its spring I' attached to a post K' operates in 95 the well-known manner to cause the wheel L'' to rotate as the result of successive energizations of the magnet. In this way the wheel is given a predetermined number of advances or units of movement in a complete revolution. This rotation will take 100 place in a clockwise direction until the energizations of the magnet L' cease. The wheel L'' is mounted on a suitable spindle

85 which projects through the front of the box and ends in a pointer such as shown in Fig. 5 adapted to coöperate with a suitable dial R. The wheel can be reversed by the 5 act of an operator in disengaging the two pawls J'', J', whereupon the spiral spring J fixed to the spindle and to the wheel in the well-known manner will cause a reversal until the wheel returns to its normal 10 position. The wheel can be stopped in any suitable manner, as for instance by having some outside member such as a pawl JJ, Fig. 3^a, engaging with the stud which carries the hair spring. The 15 disengagement of the pawls J'', J' referred to is produced in the form herein shown as the result of lifting up the bar H bracketed at E' and which carries a hanger K arranged to engage with both of the pawls; 20 and the raising of these devices is produced by the pin K''' bearing upward against the bar H whenever the operating lever C'' of Fig. 1 is raised, the said pin K''' being fastened to the said lever C'' and projecting 25 through a suitable hole xH' in the side of the indicator box.

The successive impulses are produced as follows: Every energization of the magnet described causes its armature to carry with 30 it by way of the spring connection H'' the hanging element F' bracketed at F and carrying a contact spring F'' normally resting against a fixed contact K'' mounted upon the piece L and in series with the 35 magnet by line 5. The result is the same as produced in ordinary trembler bells, but this mechanism has been devised for the purpose of securing a slow action and moreover one the speed of which may be pre-arranged 40 within the necessary limit. By the organization shown, and by varying the length of the levers a very slow action can be produced instead of the rapid automatic rheotomic trembler effect which by reason of its speed 45 could not be followed by any ordinary step-by-step actuating apparatus such as shown in my Patent #693,013 heretofore mentioned. Therefore if current is admitted to the magnet in any suitable manner (forming 50 no part of the present invention) the magnet will attract its armature, thus impelling the wheel and at the same time breaking the circuit because this leads from the magnet by connection 5 to the contact point K'' 55 controlled by the element F', and as the result of the attraction of the armature the circuit will be broken. As soon as it is broken the armature H' and element F' will be retracted by springs 6 and H'', re-closing 60 the contact at K'', and the operation described will be repeated and thus for every repetition of this operation the wheel will advance one step, and one impulse will be sent along the line. The transmitting or 65 circuit-controlling apparatus at the distant

station will thus receive successive impulses, and an apparatus of a suitable type will be operated by these impulses until a change is made in the current combination produced at the sub-station so as to terminate the regularity of these impulses. At this time the 70 position of some suitable member moving with the step wheel L'' (as for instance a pointer centered at A in Fig. 5) will show as compared with its position at the beginning of an operation how many steps have been taken, and hence the condition of the transmitting or controlling apparatus at the beginning of operations. In other words, 75 where such transmitting apparatus is used to send variable signals, the indicator hand will thus correspond to the signal set, and if the transmitter has a dial, then the markings on the receiver dial as in Fig. 5, having been made to correspond thereto, will be indicated by the hand on the spindle of the step wheel, which projects through the center of Fig. 5. 80

The organization shown is often used in connection with means for calling attention 90 in a general manner to the fact that a current change has taken place at a distant station. A device for this purpose is shown in Figs. 1 and 2, in which the target or disk S. P. is designed to be raised into view so 95 as to show through the window R' of Fig. 5. The target is fixed to a lever S. R. a right-angled extension of which S. R' tends under force of attached spring S'P' to throw this target upwardly into view before window 100 R', shown in Fig. 5. The target is normally held in its lower position shown in Figs. 1 and 2 by an armature G''' of a magnet O''. The armature G''' is normally kept in retractive position by a spring H''' so as to 105 bear against the upper side of the target SP as shown, and it is obvious that when this magnet is attracted by its armature the target will be released for upward movement. To restore the parts to normal position, that 110 is with the target down, I have provided an oscillating lever L''' pivoted at N^o and having its rear end connected by link DK to the hand-operated lever C''. The forward end of the lever L''' is provided with a pivoted toe T normally held in line with the lever by springs US and US'. When toe T is carried upwardly by the movement of its lever L''', it strikes a projection VS upon the end of the target and passes the same 115 without disturbance to the target, but when said target is up the downward movement of the toe T engaging projection VS carries said target with it and thus resets it beneath the trigger armature G'''. These restoring 120 movements of lever L''' are produced by the operation of the hand lever C'' by reason of the connecting link DK as shown. 125

The movement of the target SP may also be suitably arranged to control suitable 130

switching mechanism of the main circuit, for instance by having said circuit led through the metallic portion of arm SR, and thence to a contact W'', so that when the target is thrown up into indicating position the main circuit will be broken at this point. This break in the main circuit taking place simultaneously with an indication from a distant station is useful in signaling systems such as described in my copending application, Serial Number 93,281 $\frac{1}{2}$. Since the particular arrangement of circuits for operating the present apparatus form no part of the present invention, they need not be more particularly described.

It will be readily understood from the foregoing description, that a forward movement in a clockwise direction of ratchet L'' and indicator 85 connected thereto will take place as long as magnet L' is energized. In this way a transmitted signal from a distant station, for instance a hotel room, is indicated at the receiving station or office of the hotel, and it is sometimes desirable to group together signals of certain kinds and to keep an account of which group a transmitted signal belongs in. For example, a hotel clerk at the office may have a dial on his receiving instrument which is divided off into articles costing 5 cents, other articles costing 10 cents, and others 15 cents, and so on,—all articles of the same price being included within the same group on the dial as indicated in Fig. 5. After a signal has been received and the receiving instrument has been restored to its original position, the clerk might possibly forget in which group the signal was given and consequently omit to charge the guest or customer with the proper amount. The devices therefore shown in Figs. 3 α , 4, 5, 6 and 7 are particularly designed to enable a better account to be kept of such signals, and to automatically register the total cash represented by articles which have been signaled from distant stations.

It has heretofore been mentioned that the wheel L'' when released from its driving pawls J'', J' will be reversed by spring J until some part thereof, such as its hair spring stud, is engaged and held by a further retaining pawl JJ of Fig. 3 α . This retaining pawl JJ is pivoted to some part of the frame, as shown in Fig. 3 α , and its tail is adapted to be engaged by projection T'' on hanger K. Other projections of hanger K,—T'' and T α , in a similar manner engage tail portions of pawls J' and J'', so that when the hanger K is lifted, pawls J' and J'' will be released from ratchet J, while pawl JJ will be thrown into the path of a projection 19 on said wheel J in an obvious manner. As heretofore described, the hanger K is moved by means of its connection to swing arm H,

said arm H in turn being raised by pin K''' extending through slot XH' of the plate E'''. The pin K''' is, as shown in Fig. 1, carried on the operating handle C'' and therefore the up and down restoring movement of this handle C'' produces the up and down movement of hanger K, Fig. 3 α . The parts are also preferably constructed so that when pawl JJ is lifted to release its pin 19, the wheel J moves forward sufficiently before being engaged by pawls J', J'', to carry pin 19 past the hooked end of JJ. In this way the pawls JJ and J' and J'' act as a step by step escapement with every up and down movement of hanger K, each step of movement being of course the distance between the pins or stops engaged by hook JJ. In the form shown in Fig. 3 α , I have shown several of said stops comprising pins 19, 20, 21, 22 and 23 projecting from the face of wheel J and adapted to be engaged by pawl JJ, as above described. The purpose of having a number of these stops will now be described. If every article upon the dial shown in Fig. 5 was of the same price, for instance 5 cents, a single stop on the wheel J would be sufficient, because at every restoration of said wheel to normal position the operator would know afterward that some 5 cent article had been called for by signal, and if the clerk therefore merely kept account, either manually or by an automatic counter, of the number of times which he restored his instrument by moving up and down handle C'', he would know how many multiples of 5 cents should be charged up. If, however, the receiving dial contains articles the price of which is a multiple of 5, such as 10 cents, 15 cents, and so on, and some article costing 15 cents is signaled for, there should be an arrangement to require the clerk in completely restoring the instrument to move the handle C'' three times instead of once, since the article signaled for costs three times 5, or 15 cents. This is the purpose of the several pins upon the face of ratchet J, and in this manner if account is kept of every time the handle C'' is moved in restoring the instrument, an accurate account of all 5 cent articles, or those costing a multiple thereof, will be known. The number of movements of lever C'' may of course be kept mentally, but they are preferably registered by an automatic counter, hereinafter referred to.

The action of the pins 19, 20, 21, 22 and 23 will now be clear, but may be briefly summarized as follows. Pin 19 may be regarded as the home stop or zero position. Pin 20 should be placed to correspond with the division between the 5 and 10 cent articles, pin 21 to correspond with the division between 10 and 15 cent articles, and pin 23 to correspond with the division between 15 and 20 cent articles. If, then, a

20 cent article is signaled for, the dial connected to shaft 85 will be driven around to some one of the articles, such as *a*, *b*, *c*, within this group. To restore the instrument the clerk lifts handle *C*' once and the dial pointer partially returns until pawl *JJ* catches the next pin 23. To completely restore the pointer of the dial to zero position, therefore, the handle *C*' must be moved 5 as many times as there are pins 21, 22 and 10 23 from the home position. Consequently to bring the dial back from the 20 cent group, the handle *C*' must have been lifted 15 four times, which indicates that an article costing four times 5 has been signaled for. It is of course obvious that this arrangement may be applied to various uses widely different from that here shown, the present 20 particular description being given merely to clearly point out the operation of my group signaling and registering device.

A device for automatically counting and registering the several movements of the restoring lever is represented more or less diagrammatically in Figs. 4, 5 and 6, in which 25 *A*" indicates an ordinary form of counting mechanism having an operating plunger *B*" which is depressed for actuating the same in the usual way. A bell crank lever pivoted at *B*' has one end extending above the plunger *B*"', and its other end in the path of a pivoted element *P*"'. The element *P*"' is adapted to be given a partial rotation by means of a key stud *C*, whereby the bell crank lever *B*' is moved to actuate the counter. The key stud *C* may be turned either by a key as shown at *C*' in Fig. 7, or by a 30 permanently attached handle indicated at *C*"', Fig. 5. The key stud *C* is also preferably arranged to actuate, by means of cam engagement, a slide bar *C*"', which slide bar in turn is connected to the stud *K*"' for lifting arm *H* in the restoring movement. The slide bar *C*"' is guided in straps *D*"', 35 and at its lower end rests upon a spring *D* which is lifted by the cam *D*"' of the key stud *C*, when said key stud is turned. By this construction the rotation of the handle *C*"' automatically restores, or partially restores, the instrument and at the same time 40 keeps accurate count upon a numbering machine of the restoring movements. Of course a continued rotation of said crank *C*"' will very quickly restore the parts to zero and register on the numbering machine the proper multiples of 5 cents representing the article signaled for.

I do not mean to limit myself to the precise arrangement shown, either of the 45 elements alone, or of the manner of their coöperation with each other; thus, for example, the circuit-breaking drop operating with the indicating disk *S P*, and directly restored by the operation of the lever *C*' 50 may be restored by any other moving part,

or the numbering machine may be worked by the up or the down stroke of that lever; or the rheotome may be controlled in another manner. These examples are here given for illustration merely.

What I claim is:—

1. An electric indicator comprising a moving member constructed to have a predetermined number of units of forward motion from a normal position, a magnet controlling this motion, means for holding said member in the position into which it has been moved and means constructed to restore it to its normal position comprising devices for producing successive portions of such restoration said devices operating to cause such restoration to require two or more partial restoring movements of the said member to an extent greater than that of the said unit of motion and means for recording the 70 number of such partial restoring movements. 80

2. A magnetically controlled wheel constructed to move forward by steps or units of motion in combination with means for reversing the motion of the wheel comprising 90 devices to check this reversal at successive points each of which corresponds to several of said units of forward motion.

3. In an indicating mechanism, in combination, an indicator, an electro-magnet, 95 means controlled thereby for giving said indicator a step-by-step advance to indicate a signal, a signal member normally held in a non-signaling position and controlled by said magnet, and a member independent of 100 control by said magnet arranged to restore said indicator and said signal member simultaneously to their normal positions after the signal has been given.

4. In an indicating mechanism, in combination, an indicator, an electro-magnet, means controlled thereby for giving said indicator a step-by-step advance, a signal normally held in a non-signaling position and controlled by said magnet, and a circuit 105 through said magnet arranged to be broken by a movement of said signal.

5. In an indicating mechanism, in combination, an indicator device, electro-magnetic means for advancing said indicator device 110 into a succession of different indicating positions having a different significance, and a movable counter for counting the number of successive indicating positions assumed by said indicator device, and thereby indicating the signaling position of said indicating device, and means associated with said counter and indicating device, for acting on the latter, such that said action on the indicator device and the action of said counter 115 are interdependent.

6. In an indicating mechanism, in combination, an indicator device, electro-magnetic means for advancing said indicator device 120 into a succession of different indicating po- 125

sitions having a different significance, means for restoring said indicator device to its normal position by a succession of movements corresponding to said different successive indicating positions, and a movable counter actuated by said restoring means for counting the number of said successive movements, and thereby indicating the signaling position of said indicating device 10 after the same has been restored.

7. A magnetically controlled indicator comprising means for moving it forward during the act of indication, a supporting base with means whereby said indicator may 15 be removably connected thereto, mechanism on said base acting to restore the indicator to its normal position, together with registering devices, all coöperating so that when the indicator is associated with said base, 20 said indicator will be brought into coöperative connection with said restoring mechanism and the registering devices; together with a circuit controlling device constructed and arranged to be brought into operation

during the actuation of the indicator and 25 registering devices.

8. In an indicating mechanism, in combination, an indicator device, means for advancing said indicator device into a succession of different indicating positions, means 30 coöperating with said indicator device so that said different indicating positions correspond to progressive regularly increasing numbers, means for returning said indicator device to its normal position after each signal 35 has been indicated thereby, and a movable counter actuated by said indicator returning means for counting the number of successive indicating positions assumed by said indicator device in giving the signal. 40

In witness whereof, I have hereunto signed my name in the presence of two witnesses, this 10th day of February, 1902.

F. BENEDICT HERZOG.
